UNITED STATES PATENT OFFICE.

CLARENCE D. COMPTON, OF NEW YORK, N. Y.

POPPET-VALVE.

1,213,590.

Specification of Letters Patent. Patented Jan. 23, 1917.

Application filed August 18, 1916. Serial No. 115,727.

To all whom it may concern:

Be it known that I, CLARENCE D. COMPTON, a citizen of the United States, and a resident of the city of New York, borough 5 of Manhattan, in the county and State of New York, have invented a new and Improved Poppet-Valve, of which the following is a full, clear, and exact description.

My invention relates to a spring-pressed 10 poppet valve, as for example, the poppet valves employed on internal combustion engines.

Particularly, the invention relates to a valve of the indicated class having means 15 whereby a turning movement will be imparted to the valve relatively to its seat in the normal operation of the valve, in order to effect a self-grinding action, by a varying presentation of the valve to its seat.

20 An object of the invention is to provide means to relieve the valve of the spring pressure when the valve is open, thereby leaving the valve more free to turn. This object is attained by effecting an indirect 25 pressure of the spring on the valve stem and causing the operation of the valve-actuating means to first relieve the spring pressure on the stem before the stem is engaged and actuated.

30 A further object of the invention is to provide means whereby to give a turning movement to the valve when relieved of the spring pressure. This object is attained in the preferred form of the invention by a 35 spring-supported weight loose on the stem and coacting means on the stem and weight to impart a slight turning movement to the weight that its momentum will tend gradually to turn the stem and valve.

40 The invention will be more particularly explained in the specific description following.

Reference is to be had to the accompanying 45 drawings forming a part of this specification in which similar reference characters indicate corresponding parts in all the views.

Figure 1 is a vertical section of a poppet valve embodying my invention, showing the 50 same applied; Fig. 2 is a side elevation, the valve casing being in section on the line 2-2, Fig. 1, the valve itself being shown at right angles to the position of Fig. 1; Fig. 3 is a detail horizontal section on the line 55 3-3, Fig. 2.

I have shown my invention applied to the poppet valve of an internal combustion engine, the numeral 10 indicating the valve of the usual form having a stem 11 and movable to and from the valve seat 12 in the 60 engine 13. The numeral 14 indicates the valve casing, and 15, the usual rocker arm for actuating the valve by an axial movement of the valve stem.

The spring 16 surrounding the valve stem 65 bears at its lower end against the top of the usual partition 17. Instead of the spring abutting at its upper end directly against the valve stem, I provide an element 18 loosely slideable on the stem and receiving the pressure of the spring. Preferably, said element is cup-shape presenting an annular flange adapted to receive the contact of the cap 19 which is engaged by the rocker arm 15. The arrangement is such that as the cap 19 is moved on the stem in the opening movement of the valve, said cap will contact with the flange of the cup 18, thereby depressing the same against the tension of the spring 16. 70 75

I provide on the stem means to be engaged by the cap 19 after the cup 18 has been displaced and the spring depressed. Advantageously, the means consists of a washer 20 on the stem and made rigid therewith by a 80 transverse pin 21. The cup 18 accommodates the washer 20 and upon closing pressure of the spring against the cup 18, said cup contacts with the washer 20, thereby closing the valve. Upon the opening of the valve the 85 cap when depressed will first displace the cup 18 thereby relieving the washer 20 and the stem of spring pressure, the continued movement of the cap serving to engage the washer 20 for depressing the stem and opening the valve. 90 95

It will thus be seen that in the open position of the valve, the stem is entirely relieved of the spring pressure and is therefore more free to turn due to the vibration imparted to the valve in the sudden opening thereof. 100

In order not to depend on the self-turning of the valve, I provide means acting, when the valve is open and thus free from the spring pressure, to turn the valve relatively to the seat. In the illustrated example, the means to impart a turning movement to the valve includes a weight 22 loose on the stem 11 and seated on a comparatively light spring 23. The weight is formed with an oblique slot 24 extending transversely there- 105 110

through, and a rigid pin 25 on the stem extends into said slot. In operation as the valve is moved axially, the pin 25 by engagement with the oblique walls of the slot 5 will tend to give a turning movement to the weight 22 which freely rests on its spring support 23 and the momentum imparted to the said weight will tend to gradually turn the valve 10 so that always there will be a 10 varying relation produced between the valve and its seat.

Having thus described my invention I claim as new, and desire to secure by Letters Patent:

- 15 1. The combination with a spring-pressed poppet valve and its seat, of actuating means for the valve initially movable to free the valve from the pressure of the spring, the continued movement of said means serving 20 to actuate the valve after being freed from the spring pressure.
2. The combination with a poppet valve and its seat, of a spring closing the valve, an element movable relatively to the stem 25 against which the spring abuts, a member on the stem to be engaged by said element, and

actuating means movable to displace the said element and then engage the said member on the stem for actuating the valve.

3. The combination with a poppet valve 30 its seat and spring, of means to free the valve of the pressure of the spring and impart an opening movement to the valve after being freed from the spring pressure.

4. The combination with a poppet valve 35 and its seat, of actuating means for the valve, a weight loose on the valve stem, and coacting means on the weight and stem to impart a turning movement to the weight.

5. The combination with a poppet valve 40 its seat and spring means acting on the valve stem and tending to close the valve, of actuating means movable to relieve the spring pressure on the stem in opening the valve, a spring-supported weight loose on the stem, 45 and co-acting means on the stem and weight to impart a turning movement to the weight upon an opening movement of the stem.

CLARENCE D. COMPTON.
